GUN COOLING VALVE

George A. Hawkins, West Lafayette, Ind., assignor to the United States of America as represented by the Secretary of the Army

Application November 30, 1945, Serial No. 632,068

4 Claims. (Cl. 89—1)

The invention relates to means for injecting water or other liquid into the chamber of a gun, operable by a conventional recoiling part of the gun; and particularly to means adapted to use on high speed machine guns such as the current models of .30 caliber and .50 caliber machine guns. An important purpose is to present a valve for delivering charges of cooling liquid to the gun, so constructed as to be readily incorporated on guns already manufactured without change of construction of the firing mechanism, and without impairing the action and efficiency of the arm. Also, it is sought to enable the operation of such weapon in the usual way, and with a minimum requirement of special service. Additional requirements which it is an aim to meet are: Lightness, compactness, durability and ruggedness, ready accessibility to parts and avoidance of interference with usual servicing and repair of the standard gun action.

It is particularly an aim to enable the operation of the invention by a recoiling part of the gun in such manner that the rate of fire will not be materially slowed, and whereby energy of recoil heretofore dissipated may be converted to the operation of the device of my invention. On account of the fact that the work required of the firing mechanism is in many cases close to the maximum for which energy is available, it is an important purpose to minimize requirements of power for operation of the device.

It is a specific object of the inventor to present a device which will supply a measured charge of liquid to the chamber of a gun after the firing of each round at the short intervals of time involved in machine gun fire.

A further important end in view is to develop a device which will store part of the recoil energy of the weapon and convert it to counter recoil force acting on the valve to return it to an initial position after recoil.

Additional objects, advantages and features of invention reside in the construction, arrangement and combination of parts involved in the embodiment of the invention, as will be apparent or understood from the following description and accompanying drawings wherein;

Figure 1 is a left side elevation partly in section of the rear part of a gun upon which my invention has been incorporated;

Figure 2 is a cross section of the pump on the line 2—2 of Figure 1;

Figure 3 is an elevation of the left side of a gun having a modified valve thereon;

Figure 4 is a top view of the gun and valve modification partly in section;

Figure 5 is a section on the line 5—5 of Figure 3;

Figure 6 is a section on the line 6—6 of Figure 3;

Figure 7 is a section on the line 7—7 of Figure 3;

Figure 8 is a rear view of the bolt of Fig. 1;

2

Figure 9 is a fragmentary longitudinal section of a modified valve, alone.

Referring more particularly to the details in the drawings, there is illustrated in Fig. 1 a conventional machine gun 10 having a barrel 70 with a chamber 71, receiver body or case 11, at the rear end of which grips 12 familiar in this gun are mounted on a back plate 13 of the receiver. At the upper part of the back plate a trigger 14 is mounted, operable between the grips as heretofore.

The back plate 13 has the usual buffer disc sleeve 15 in which elastic buffer discs have heretofore been mounted supported rigidly at the rear or outer end of the sleeve, and bearing against a buffer plate set

15 in the back plate and rearwardly yieldable to the bolt of the gun action, a form of which may be found in the patent to Browning 1,628,226. Equivalents of the discs are retained as at 16 and a buffer plate 17 mounted as before, but all the discs and the buffer plate are axially bored, so as to receive freely slidably therethrough

20 a valve stem 18 extending through the head 19 of a valve case or cylinder 20, the head being tenoned and threaded to screw into the rear interiorly threaded end of the sleeve 15 and against the discs as a rigid support 25 or seat therefor. The tenon 21 is bored at its forward end to receive a packing and gland around the stem 18, at 22, the stem 18 being snugly slidable through a reduced bore in the head. A spool valve 23 is fixed on the stem, and reciprocable in the cylinder 20. In

30 the present instance the cylinder is shown as a bored piece closed at its rear end. The length of the cylinder bore greatly exceeds the length of the required stroke of the valve, so as to accommodate a spring of adequate length.

35 The valve body 23 is held between nuts 23' screwed on to and set with the rear end portion of the stem 18 so as to be longitudinally adjustable on the stem. The valve is formed with a relieved part 24 intermediate of its length, extending entirely around the valve,

40 its longitudinal extent being nearly equal to the maximum stroke of the valve, as will appear, leaving a cylindrical head or land 25 at the rear end, and a similar land 25' at the forward end. Land 25' engages the

45 head 19 to limit the normal forward or initial position of the valve. The valve is urged to its initial forward position by a spring 26 confined between the rear end of the valve and a screw plug 27 engaged in the rear end of the tube 20. This plug may be used to adjust the tension on the spring 26 if desired. It is cup-shaped,

50 to receive the end of the spring a distance therein so that the tube is not required to extend over the entire length of the spring. The plug has a vent port 28 therethrough by which air and leakage water may be vented in operation of the valve.

55 Inlet and outlet ports 30 and 31 are formed in opposite sides of the tube 20, located so as to be midway of the length of the land 25 when the valve is at initial position. A forward vent port 32 is formed in the lower side of the tube at its forward extremity, and this

60 port 32 may be reduced in size, if desired, to serve as a dash pot control function.

The stem 18 is in line with a part of the usual bolt 33 of the gun mechanism, and on the rear end of the bolt a striker plate 34 is mounted by means of a transverse dovetail slide bar 35 set slidably in a corresponding horizontal channel formed across the rear end of the bolt and fitted at its ends slidably between the side plates of the receiver 11. In consequence, the plate 34 is held

65 in operative position without fastening as long as the bolt is in place in the receiver. The stem 18 is extended a distance forwardly of buffer plate 17 in the path of the bolt sufficient for the latter to engage it and move

the valve land 25 past the ports 30 and 31 a distance corresponding to the time during which it is desired to keep these ports open. This time is limited at its minimum by the time of recoil of the bolt over the distance which the valve has been moved and at its maximum by the extent of movement of the bolt in operating the valve and the time required for the spring 26 to return the valve to initial position, if this return movement is slower than that of the bolt.

A supply pipe 36 is connected to the inlet port 30 and a delivery pipe 37 is extended from the outlet port 31 to the chamber 71 of the barrel 70 where the liquid delivered, as generally indicated by reference numeral 72, may be utilized in accordance with approved methods and in suitable apparatus for cooling the chamber and bore of the gun. These features comprise no novel part of the present invention and therefore are not illustrated.

In the use of this invention a source 64 of liquid under pressure is provided from which the supply duct 36 is led to the inlet port of the valve. This source may be reservoir with air chamber 65 and compressor 66, and is maintained at a pressure proportionate to the size of orifice of the jet at the gun chamber, the time within which a required quantity of liquid must be forced through the jet, and inertia and friction of the water column to be moved. These pressures may vary from 20 p.s.i. to 600 p.s.i. The quantity of water required may be three cubic centimeters per charge, more or less, according to the degree of cooling desired and the temperature of the liquid supply.

For a .50 caliber machine gun three and one half cc. or less, have been found effective.

The bolt 33 of the firing mechanism of the gun indicated travels a distance of approximately seven and one eighth inches, and the valve 23 is adjusted so that its stem will be engaged during the extreme terminal part of the recoil movement of the bolt. The valve parts and nozzle are so proportioned that, with a pressure water supply within the range of pressures indicated, the necessary quantity of water may be forced through the ports 30 and 31 while the valve is moving from initial open position to extreme rearward position and back again to cut off.

As this extent of movement of the bolt occurs in something like $\frac{1}{3000}$ second, at usual rates of antiaircraft fire, spring 26 may, if desired, be made of such strength that it will return the valve more slowly than the bolt travels by rebound from the buffer plate and propulsion of its driving spring. But this slower return movement is sufficient to close the ports 30 and 31 before completion of counter recoil of the bolt to that point where the new cartridge has been entered so far as to interfere with the water jet.

In the type of gun mentioned a recoil action separate from that of the bolt is provided for the barrel, operatively connected with the cartridge feeding means, the extent of travel of this recoil being only about one and one eighth inches; and the bolt, utilized for the loading, firing and extracting and cocking, moves independently over the greater part of its travel. The operation of my valve may tend to slow the bolt slightly due to the energy applied thereto. However, there is an initial recoil and terminal counter recoil interaction and coupling between the barrel unit and the bolt unit, including an accelerator device on the barrel unit by which impetus may be added to the movement of the bolt, and counter recoil functions of the barrel unit are adjustable so that an increment of velocity may be added to the bolt movement to compensate for the energy required in operating the valve.

In Figures 3 to 7 there is illustrated a modification of the valve mounted at the left side of the receiver 11. The receiver side plates are conventionally formed with horizontal guide slots 40 in which right and left bolt studs 41-42 reciprocate. The one at the left is extended

from the receiver sufficiently to be utilized in the operation of the valve. For this purpose a guide 43 is secured to the side plate of the receiver, having a channel 46 on its under side over the slot 40 in which a slide 44 is reciprocably engaged. This slide has a longitudinal slot 45 therein receiving the end of the stud 42 for longitudinal movement along the slot 45 and against the ends of the slot. This slot 45 is shorter than the travel of the bolt of the gun, and is proportioned so as to be engaged at its rear end by the stud 42 while the bolt is moving rearward in extraction of the fired cartridge case from the gun chamber. The guide 43 has a slot 47 open through its left side and forward end over the channel 46, and extending over a distance which is more than the difference between the length of the slot 45 and travel of the bolt.

A valve case 48 is fixed with the guide 43, having a horizontal cylindrical bore 54 therein open at its forward end. On the forward part of the slide 44, a lug 49 is formed extended outward through the slot 47 across the axis of the bore 54 and has inserted therethrough a threaded tenon 50' of a valve member 50, which consists of a rectilinear bar extended rearwardly from the lug 49. It includes a large diameter base stem part 51 which remains without the case and has a seat shoulder 52 thereon, a helical wire return spring 53 being engaged around the part 51 and confined between the seat 52 and the forward end of the case 48. A distance rearward of this seat, the valve body is reduced to the diameter 30 of the bore 54 forming a land 55, which slidably fits, and remains engaged in, the bore 54 throughout operative movements of the valve. Rearward of the land 55 a circumferential relieved part 56 of the valve extends over a distance equal to the travel of the valve, affording a 35 clearance or annular channel 56' within the bore, and this terminates at a rear end land 57 fitted to the bore 54 slidably.

With the part described proportioned and arranged as shown, the land 57 will have an extreme operated position adjacent the rear end of the bore 54 in the case 48 and an initial, forward closed position with the land 55 extending a distance into the bore 54. At a point intermediate of the rear land 57 while at its stated initial position an inlet port 58 is formed through the case to the bore 54 and an opposite outlet port 59 is formed from the bore 54 through the case, into which is connected a discharge pipe 60 which is extended forwardly beside the gun to whatever device there may be used for introducing discharged liquid into the chamber 71 of barrel 70 of the gun as generally indicated by reference numeral 72. The details thereof are omitted in the present application since they form no part of the invention here claimed. A high pressure liquid supply conduit 61 is connected into the inlet port 58 of the valve case, leading from any suitable pressure liquid supply not shown, but which may correspond to the source 64 before described.

For the purpose of enabling some adjustment of the timing of the function of the valve the valve may be 60 made adjustable longitudinally on the lug 49, nuts 62 being engaged and adjustable on the tenon 50' on each side of the lug 49.

A bumper or stop 67 is provided at the forward end of the channel 43, against which the slide 44 may engage when at the forward limit of its movement. This 65 may be a separately attached piece or a part of the guide 43.

Figure 9 illustrates the valve case 20' constructed with the inlet port 30' longitudinally forward of the outlet 70 31 so as to lie just forward of the rear land of the valve when the latter is at the forward limit of its movement defining its initial position. The outlet port 31 is still midway of the rear land of the valve 23, at this position.

This arrangement effects a better balancing of the

valve, pressures being equal on all sides and against the inner faces of both lands.

In the rear end of the case a vent port 63, shown in Figs. 3 and 4, is formed therein at the lower side to relieve air pressure and drain leakage liquid from the bore behind the valve, and to function otherwise as in the case of the port 32 before described.

In the operation of the gun equipped with my invention, in the reciprocation of the bolt, when it moves in recoil from battery position, it extracts the empty cartridge case, drawing the same rearwardly from the chamber of the gun. Before the case clears the chamber it is intended that the bolt stud 42 shall engage the rear end of the slot 45 and thereby move the land 57 clear of the ports 58-59. The bolt then has a further recoil movement carrying the empty cartridge case and valve with it. After the cartridge case is ejected, a further recoil movement of the bolt occurs, still moving the valve, by which movement also a new round is extracted from the cartridge belt, preparatory to its being thrust forward into the empty chamber. The valve will then be at its rear limit or full stroke operated position. The bolt now counter recoils, and performs this loading function. The length of the slot 45 is such that the bolt stud engages the forward end of this slot 45 while the point of the round is entering the chamber, or shortly before, so that the rear land 57 is moved forward, and will be returned to cut-off relation with the ports 58-59 while the round is partly entered in the chamber. By utilizing the maximum possible time during movement of the bolt to keep the valve open, the requirement of pressure in the supply is minimized, and a good jet function made possible with low pressure in case such a device is used at the gun chamber.

While I have disclosed the invention in detail in its best construction perfected and used by me, it will nevertheless be understood that this is purely exemplary and that modification of construction, proportions and arrangements of parts, substitution of materials and equivalent mechanical or otherwise, fall within the spirit of the invention in consonance with the appended claims, wherein

I claim:

1. The combination of a machine gun of the character described and a bolt-operated water injection control valve comprising a gun framing, a bolt reciprocable therein, a guide parallel to the bolt path externally of the framing, said bolt having a stud projecting laterally therefrom exteriorly of the framing, a slide reciprocable in the guide having a part in the path of the stud rearwardly of the latter, a spring to return the slide to a forward initial position, means to limit forward movement of the slide, a case cylinder fixed with the framing

parallel to the guide, a valve reciprocable therein having a stem part extended forwardly from the cylinder, a lug fixed on the slide across the axis of the case, said stem being fixed to the lug, an inlet port formed in the case forwardly of the rear part of the valve when at initial position, a high pressure liquid supply connected therewith, an outlet port formed in the case spaced from the inlet port and located intermediately of the rear portion of the valve when the latter is at said position, and a discharge conduit from the outlet port to the gun chamber.

2. In an automatic firearm having a receiver body, a barrel affixed thereto, and a bolt slideable therein in recoil and counter recoil, a cooling system for said barrel comprising a valve case affixed to said body parallel with said bolt, diametrically opposed inlet and outlet ports provided in said case, said inlet port connected with a high pressure coolant source, said outlet port communicating with said barrel, a spool type valve slideable within said case and having lands formed at each end thereof, the rearward land normally resting adjacent said diametrically opposed ports, spring means biasing said valve forwardly, a valve stem connected with said valve and extending forwardly of said valve case externally thereof, the said bolt being operative in lost motion relationship with said stem to move said stem rearwardly during the latter part of the bolt recoil stroke, the distance between said lands being substantially equal to the said operative portion of said bolt stroke, the system being operative to spray a coolant into said barrel in the interval between first round fired and second round inserted into said barrel.

3. The invention according to claim 1 wherein the said inlet port is formed in said cylinder case in diametric opposition to said outlet port.

4. The invention according to claim 1 wherein an elongated slot is provided within said slide, said lug adapted to rest normally against the forward end of said slot and to engage the rearward end of said slot during the latter part of the bolt recoil stroke.
